UNITED STATES PATENT OFFICE.

ORVILLE S. HARMON, OF NEW YORK, N. Y.

BICYCLE-SADDLE.

SPECIFICATION forming part of Letters Patent No. 660,215, dated October 23, 1900.

Application filed May 21, 1898. Serial No. 681,347. (No model.)

To all whom it may concern:

Be it known that I, ORVILLE S. HARMON, a citizen of the United States, residing at the city of New York, (Brooklyn,) in the county 5 of Kings and State of New York, have invented certain new and useful Improvements in Bicycle-Saddles, of which the following is a specification.

My invention relates to bicycle-saddles.

10 I will describe a bicycle-saddle embodying my invention and then point out the novel features in the claims.

In the drawings, Figure 1 is a perspective view of a bicycle-saddle embodying my invention. Fig. 2 is a bottom view thereof. Fig. 3 is a detail sectional view on the line 3-3, Fig. 1. Fig. 4 is a view of the front end of the saddle. Fig. 5 is a bottom view of a modified form of saddle. Fig. 6 is a bottom 20 view of a saddle having a seat portion of perforated metal.

Similar letters of reference designate corresponding parts in all the figures.

A represents the seat portion of a bicycle-saddle, B a frame which carries the seat portion, and C a spring for supporting the frame and seat portion from a clamp D, which is connected with the seat-post of a bicycle.

The seat portion A is of woven wire and 30 tempered to render it resilient, which resilience tends to preserve the normal shape of the seat portion while not in use. The seat portion is secured to the frame B at all points of its periphery, and it is curved upwardly 35 and outwardly from the frame, so as to be protuberant between its upper and lower portions. The purpose of this protuberance is to provide for a better cushion effect in the seat portion. The protuberance also presents 40 a rounded and yielding surface against which the limbs have to bear while in the act of pedaling. As shown, the curved or protuberant portion is more pronounced at the front part of the saddle than at the rear, and hence the 45 seat portion will be thicker at this part. This increased thickness is provided at this part owing to the necessity of having the saddle yield more at this part than at the rear. To obtain the best results, the curve b' in the 50 seat portion gradually increases in its radius from the rear toward the front at the sides of the saddle, attaining its greatest radius at the

front of the saddle, as shown at b². The radius of the curve may then decrease along the horn of the saddle. A cover E, of any suitable 55 material, may be provided for the seat portion.

The frame B of the saddle is preferably of wire, which is flexible, thereby permitting the saddle yielding to any motion of the body of the rider while in the act of pedaling. The 60 frame is preferably made from a single piece of wire, which is bent to the desired shape. In the drawings the frame is shown as having two layers of wire (see Figs. 1 and 3) and loops b³, which extend across the frame to 65 strengthen it without at the same time interfering with the flexibility of the frame. The periphery or edge of the seat portion is held between the two layers of wire, and the periphery or edge of the seat portion and the 70 two layers of wire are held together by means of a wire b⁴, which is wound around the two layers of wire and passed through the interstices of the seat portion. This arrangement of securing the seat portion to the frame will 75 cause the frame to take up any strain that is put upon the seat portion. The wire b⁴ is also employed to bind the ends of the loops b³ of the frame.

The spring C may be of any desired shape. 80 The ends are secured in the clamps F, so that a yielding support will be provided for each side of the front and rear central line of the saddle. The clamps F are connected with the loop b³ of the frame.

In Fig. 5 I have shown a modified form of frame for the seat portion. The frame is made from a single piece of wire, which is bent to form the supporting-ovals b⁴, which are connected to each other by the cross-piece b⁵. A 90 seat portion A' is secured to each of the ovals by a wire, as hereinbefore described, and each seat portion is shaped to produce the cushioning effect hereinbefore described. In this form of saddle the attaching-clamp F', 95 employed for securing the frames to the spring C', is riveted to the frame to serve as a brace.

A convenient way for forming the seat portion and frame is to give them the desired shape when they are in a soft and untempered state. They are then united or connected and tempered to produce the resiliency of the seat portion and the flexibility of the frame.

It is obvious that instead of having the seat portion of woven wire suitably - perforated sheet metal may be employed. The sheet metal if shaped as hereinbefore described in 5 connection with the woven wire and secured to a suitable frame would possess the same advantages and produce the same results as does the woven wire. A saddle so formed is shown in Fig. 6, wherein A represents the 10 seat portion, of perforated sheet metal, and B the frame, to which the seat portion is secured.

What I claim as my invention is—

1. In a bicycle-saddle the combination of a 15 suitable frame, and a seat portion of tempered wire, curved protuberantly between the upper and lower portions, said seat portion being made thicker at the front than at the rear portion.

2. In a bicycle-saddle, the combination of a 20 suitable frame, and a seat portion of tempered wire, curved protuberantly between the upper and lower portions, said seat portion being more protuberant at the front than at the rear 25 portion.

3. In a bicycle-saddle, the combination of a 30 suitable frame, and a seat portion of tempered wire curved protuberantly between the upper and lower portions, said seat portion being made thicker and more protuberant at the front than at the rear portion.

4. In a bicycle-saddle the combination of a 35 suitable frame, a seat portion of woven wire fastened to said frame and curved protuberantly between the upper and lower portions, the said wire being tempered so that its resilience will tend to preserve the normal shape 40 of the seat while it is not in use.

5. In a bicycle-saddle the combination of a 45 suitable frame, a seat portion of wire curved protuberantly at its front and sides between the upper and lower portions of said frame, the wire of the seat being tempered so that its resilience will tend to preserve the normal shape 50 of the seat while it is not in use.

6. In a bicycle-saddle, the combination of a frame formed from a single piece of wire that is bent to have two layers of wire at all parts of the frame, and a seat portion of woven wire, 55 the edge of which is curved inwardly and held between the two layers of wire of the frame,

whereby the frame will take up the strain put upon the seat portion, substantially as described.

7. In a bicycle-saddle, the combination of a 55 frame formed from a single piece of wire that is bent to have two layers of wire arranged one above the other at all parts of the frame, and a seat portion of woven wire, the edge of which is curved inwardly so as to have it held 60 between the two layers of wire, whereby the frame will take up the strain put upon the seat portion, substantially as described.

8. In a bicycle-saddle, the combination of a 65 frame made from a single piece of wire that is bent to have two layers of wire at all parts and loops which extend across the frame on each side of the front and rear middle line thereof, a resilient seat portion having its edge held between the two layers of wire of 70 said frame, and a supporting-spring, said supporting-spring being attached at its end to said loops, substantially as described.

9. In a bicycle-saddle, the combination of a 75 suitable frame, and a seat portion of tempered woven wire having a continuous periphery which is secured to said frame at all points of its periphery, said seat portion being curved upwardly and outwardly from the frame at the sides and front thereof, and said 80 curve having a gradually-increasing radius beginning from the rear of the frame and ending at the front, and then gradually decreasing along the horn of the saddle.

10. In a bicycle-saddle, the combination of a 85 suitable frame, and a seat portion of tempered woven wire having a continuous periphery which is secured to said frame at all points of its periphery, said seat portion being curved upwardly and outwardly from the 90 frame from its periphery, and said curve having a gradually-increasing radius beginning at the rear of the frame and ending at the front thereof, substantially as described.

In testimony whereof I have signed my 95 name to this specification in the presence of two subscribing witnesses.

ORVILLE S. HARMON.
